UNITED STATES PATENT OFFICE.

FRANK X. PELEGREN, OF BELLINGHAM, WASHINGTON, ASSIGNOR TO GUSTAVE LIDSEEN, OF CHICAGO, ILLINOIS.

CARRYING CASE FOR GLASSWARE.

Application filed March 15, 1923. Serial No. 625,176.

To all whom it may concern:

Be it known that I, FRANK X. PELEGREN, a citizen of the United States, and formerly a resident of the city of Chicago, in the 5 county of Cook and State of Illinois, and now a resident of Bellingham, Whatcom County, Washington, have invented certain new and useful Improvements in a Carrying Case for Glassware; and I do hereby 10 declare that the following is a full, clear, and exact description of the same, reference being had to the accompanying drawings, and to the numerals of reference marked thereon, which form a part of this specification.

Heretofore cases have been made for holding a bottle and a number of drinking glasses in convenient shape for carrying. A disadvantage in these carrying cases is found in 20 the fact that they must be carried steadily and right side up to prevent displacement, rattling and possible breaking of the glassware. The glasses used for serving certain beverages are made of very thin material, 25 so that they are very fragile. Also it is common practice to use for such beverages a bottle and a set of glasses that are expensively ornamented so that the breakage must be avoided if possible.

It is an object of the present invention to provide a means whereby such a carrying case will hold the glasses and bottle firmly in place without exerting any excessive pressure on them, whereby the carrying case 35 may be inverted or shaken or otherwise roughly treated without danger of injury to the glassware.

It is a further object of this invention to devise such an anti-rattling arrangement for 40 a carrier of a shape which has proved popular.

Other and further important objects of the invention will be apparent from the disclosures in the drawings and the accompanying specification.

The invention (in a preferred form) is illustrated on the drawings and hereinafter more fully described.

On the drawings:

50 Figure 1 is a top plan view of the case with the cover open.

Figure 2 is a vertical section.

As shown on the drawings:

The case 10 is provided with a hinged 55 cover 11. While these may be of any de-

sired shape, I have illustrated a case and cover that make a spherical container with a flat bottom. The cover is provided with a handle 12 for convenience in carrying the case and with a lock 13 for securing the cover in closed position. The case contains a plate 14 provided with a central hole to fit a bottle 15, and with a circular series of holes to fit tumblers or other glasses 16. Preferably the body of the bottle is tapering in 60 order that it may be received in the hole even though the several bottles used may vary in size slightly. The glasses 16 are made tapering for the same reason.

Secured to the cover is a plate 17. This 70 securing is done by providing the plate with a downwardly turned flange 18 which fits the interior of the cover. The flange may be secured by soldering, spot welding, riveting, or in any other desired way. Cemented or 75 otherwise secured to the under side of the plate 17 is a sheet of felt 19. In the center of the plate 17 and the felt 19 are cut away to afford a central hole, the edges of which are beveled to fit the shoulder of the bottle 15. 80 On the side farthest from the hinge, this hole is enlarged as shown at 20 to permit the plate to pass the top of the bottle when the cover is moved about its hinge.

In the operation of the device, with the 85 cover open, the bottle and glasses are put in place in their respective holes in the plate 14 and the cover is then closed by rotating it about its hinge. During this rotation, the edge of the enlargement 20 passes the top of 90 the stopper of the bottle, which is preferably of the ground-glass type. When the cover is closed, the felt 19 comes against the tops of the glasses and presses them firmly into their holes in the plate 14. The yielding character of the felt and the springing or resili- 95 ent character of the plates 14 and 17 enable small differences in the height of the tops of the glasses to be accommodated. The felt at the beveled edge of the central hole contacts with the shoulder of the bottle, and a similar yielding action permits slight variations in the height of the bottle.

With the cover closed and the felt pressing against the bottle and glasses in this 105 way, the lock 13 is operated to fasten the cover in place. The carrier case may then be transported by means of the handle 12 and no motion of the glasses or bottle relative to the case can take place. If, during 110

this transportation, the case receives a blow, the cushioning action of the felt and the resilient character of the plates 17 and 14 will prevent this blow from injuring the glassware. If the case is inverted, the plate 17 holds the bottle and glasses from falling. The stopper in the bottle will not fall out when inverted because of the ground-glass joint between the stopper and the bottle.

10 When it is desired to use the glassware, the case is unlocked and the cover 11 tilted back about its hinge, during which action the enlargement 20 in the central hole enables the cover to escape the top of the bottle. The bottle and glasses may then be lifted out, or, if desired, the bottle may be lifted out and the contents poured into the glasses while they remain in the case. In the latter way of using the device, the case itself may serve 15 as a tray for passing the glasses to those who are to partake of the beverage.

15 I am aware that numerous details of construction may be varied through a wide range without departing from the principles of this invention, and I therefore do not purpose limiting the patent granted, otherwise than necessitated by the prior art.

20 I claim as my invention:

1. In a carrier case, a body, a cover hinged

thereto, means in the body for supporting a number of glasses with their upper ends in approximately one plane, a plate secured in said cover and parallel to said plane when said cover is closed, and a packing device mounted on said plate for contact with the tops of said glasses.

2. In a carrier case, a body, a cover hinged thereto, means in the body for supporting a number of glasses with their upper ends in approximately one plane, a plate secured in said cover and parallel to said plane when said cover is closed, a packing device mounted on said plate for contact with the tops of said glasses, said plate having a central opening, and means in the body of said case 45 for positioning a bottle in the center with its top extending above the plane of the top of the glasses, whereby when the cover is closed the top of the bottle will project through said opening.

50 In testimony whereof I have hereunto subscribed my name in the presence of two subscribing witnesses.

FRANK X. PELEGREN.
